J. W. KAUFMANN,
BAG FASTENER,
APPLICATION FILED DEC. 14, 1918.

1,301,452.

Patented Apr. 22, 1919.

UNITED STATES PATENT OFFICE.

JOHN W. KAUFMANN, OF BALTIMORE, MARYLAND.

BAG-FASTENER.

1,301,452.

Specification of Letters Patent. Patented Apr. 22, 1919.

Application filed December 14, 1918. Serial No. 266,769.

To all whom it may concern:

Be it known that I, JOHN W. KAUFMANN, a citizen of the United States, and a resident of Baltimore, in the State of Maryland, have 5 invented certain new and useful Improvements in Bag-Fasteners, of which the following is a specification.

My invention is an improvement in bags, and has for its object to provide mechanism 10 to be used in connection with bags of any character, for securely connecting the parts of the frame at the ends, that is, on opposite sides of the lock, the said mechanism comprising spring controlled catches arranged 15 to be released by push buttons or the like outside the bag, and wherein means is provided in connection with the said mechanism for normally holding the catch in release position after it has been released until the 20 parts of the frame are separated for the opening of the bag, the separation of the said parts releasing the restraining means for the catch and permitting the spring to function to hold the catch in normal locking 25 position.

A further object of the invention is to provide a neat, simple and inexpensive catch which will be within the bag, thus permitting a neat finish of the bag without bulky 30 protuberances at the ends of the frame.

In the drawings:

Figure 1 is a perspective view of one end of the bag provided with the improved catches;

Fig. 2 is a transverse vertical section through the catch;

Fig. 3 is a section at right angles to Fig. 2;

Fig. 4 is a perspective view of the catch 40 and its operating mechanism;

Fig. 5 is a perspective view of the restraining means;

Fig. 6 is a view similar to Fig. 2, showing the catch released.

The present embodiment of the invention 45 is shown in connection with a bag 1 of ordinary construction, having the closing flaps at its top, which are supported by the usual metal frame, the said frame consisting of a portion or section 2 of angular construction which carries the catch, and a portion or section 3 which carries the keepers for engagement by the catch. The catch is mounted in a suitable casing 4 which has flanges 5 at its 55 ends riveted or otherwise secured to the frame part 2, and the catch comprises a bar

6 having upon its upper face a pair of up-standing lugs 7, each lug having the face at one side edge of the bar perpendicular, the other face dipping or inclining toward the 60 bar.

These catch lugs are adapted to be engaged by slots in keepers 8, a keeper being provided for each lug, and the keepers are secured to the portion 3 of the frame. The 65 bar 6 has a pair of depending pins 9, which pass through openings in the bottom of the case 4, and coil springs 10 encircle the pins between the bottom of the casing and the bar, the springs acting normally to force the 70 bar upwardly.

In closing the bag, it being understood that the parts 2 and 3 of the frame are hinged together in the usual manner, the keepers at their free ends engage the inclined 75 faces of the lugs 7 and depress the bar 6 against the resistance of the spring, until the lugs have entered the slots of the keepers, when the springs immediately force the bar upward and the parts of the frame are 80 locked together.

A push button 11 is provided for releasing the catch lugs, the said button extending upwardly from the center of the bar 6, between the lugs 7, and this button passes 85 through an opening in the horizontal portion of the angle plate to and through an opening in an escutcheon or housing plate 12 which is secured to the top of the angle plate 2 outside of the leather covering. With this 90 construction, to release the frame parts, downward pressure is made upon the push button, thus depressing the bar 6 and releasing the lugs 7 from the keeper. Since the greater portion of bags have a spring lock, 95 it will be obvious that in order to open the bag the catches must be held released while at the same time the lock is released, a somewhat troublesome operation.

Were means provided for holding the 100 catches in release position when the bag were open, it would be necessary to release such restraining means before the bag could be completely closed. In order to obviate this difficulty I provide means for temporar- 105 ily restraining or holding the catches in release position until the bag is opened, that is, until the frame parts are separated, and the arrangement is such that the separation of the frame parts releases the restraining 110 or holding means, permitting them to function in a normal manner when the bag is

again closed. In order to obtain this result I provide a plate 13 having an upstanding lug 14 at its center and having openings 15 at its ends for permitting the passage of 5 the pins 10.

Referring especially to Fig. 2, it will be noted that the under face of the bar 6 is beveled, the said face inclining downwardly from the attached side of the part 2 toward 10 the free side. The plate 13 rests upon this beveled face, and since the lug 14 is substantially perpendicular to the plane of the plate, it will be obvious that when the plate is held closely against the under face of the 15 bar by the springs, it will tend to throw the lug 14 outwardly away from the adjacent face of the bar. This lug 14, when the plate is in place beneath the bar, with the pins 10 extending through the openings 15, is in 20 position to engage between the keepers 8, as shown in Fig. 2, so that the lug does not interfere with the closing of the bag.

The keepers may be integral with the frame part 3, or they may extend in from 25 a separate plate 16 secured to the frame part as shown in Fig. 2. In either case a web is provided between the keepers, the said web extending over the upper edge of the frame part 3 and slightly over the upper edge of 30 the adjacent wall of the casing 4 a sufficient distance to be engaged by the lug 14 when the catch is moved into release position. With this arrangement, when the bar 6 is depressed by the push button a sufficient distance 35 to release the catch lugs from the keepers, the lug 14 which is caused to swing outwardly away from the bar 6 as above stated, will engage beneath the web 17, and will hold the bar with the catch lugs in release position. So long as the bag is closed, 40 the catch lugs will be so held. The web 17 is, however, connected with the frame part 3 and moves therewith, and when the bag is opened by moving the frame parts away 45 from each other, the lug 14 will be disengaged from the web, and the catch supporting bar 6 will move with the catches into normal position, so that it is again ready to lock when the frame parts are closed. All 50 of the catch is within the bag, it being only necessary for the push button to protrude, and it will be obvious that the bag may be given a very neat appearance with such construction.

55 I claim:

1. In a bag, the combination with the hinged frame members, of a catch for connecting the said members near their ends, each catch comprising a spring supported 60 vertically movable bar having catch lugs, and supported by one frame member, keepers for engaging the catch lugs supported by the other frame member, the lugs being beveled to be depressed by the keepers when 65 the bag is closed, a plate mounted to rock

on the under face of the catch supporting bar and normally pressed toward the bar by the spring support of the bar, said plate having an upwardly extending lug adapted to be rocked outwardly away from the bar 70 by the spring support of the bar when downward pressure is made upon the bar, the other frame member having a web between the keepers for engagement by the lug to temporarily hold the catch bar in inoperative 75 position, said bar having means extending outside of the bag for operating the same.

2. In a bag, the combination with the hinged frame members, of a catch for connecting the said members, said catch comprising a spring operated latch bar carrying a catch and supported by one of the frame members, the other frame member supporting a keeper for engaging the catch, a plate 85 mounted to rock on the bar and having an outwardly extending lug normally pressed outwardly by the spring support of the latch bar and adapted to engage the other frame member to hold the latch bar depressed and 90 releasable from the frame member by the separation of the said members, said catch being within the bag and the latch bar having means extending outside of the bag for operating the latch bar. 95

3. In a bag, the combination with the hinged frame members, of a catch for connecting the said members, said catch comprising a spring operated latch bar carrying a catch and supported by one of the frame 100 members, the other frame member supporting a keeper for engaging the catch, a plate mounted to rock on the bar and having an outwardly extending lug normally pressed outwardly by the spring support of the latch 105 bar and adapted to engage the other frame member to hold the latch bar depressed and releasable from the frame member by the separation of the said members.

4. In a bag, the combination with the 110 frame members movable with respect to each other into open and closed position, of a catch for connecting the frame members, said catch comprising a catch member carried by one frame member and a keeper carried by 115 the other frame member, the catch member being spring controlled to engage the keeper when the frame members are moved together, and means in connection with the catch member and movable therewith for 120 engaging the other frame member to hold the catch member in release position and releasable by the separation of the frame members.

5. In a bag, a latch for connecting the 125 frame members comprising a spring catch carried by one of the frame members and engaging means for the catch carried by the other member, and means in connection with the catch for engaging the other frame mem- 130

ber to hold the catch in release position and released by the separation of the frame members, the engagement of the restraining means for the catch member being controlled by the releasing of the catch into engaging position.

6. In a bag, a latch for connecting the frame members comprising a spring catch

carried by one of the frame members and engaging means for the catch carried by the other member, and means in connection with the catch for engaging the other frame member to hold the catch in release position, said means being released by the separation of the frame members.

JOHN W. KAUFMANN.
